SAFETY RAZOR

Nicholas Testi, Boston, Mass., assignor to Gillette Safety Razor Company, Boston, Mass., a corporation of Delaware

Application June 1, 1944, Serial No. 538,321

9 Claims. (Cl. 30—65)

This invention relates to safety razors of the type having cooperating blade-clamping members between which a thin flexible blade is clamped and supported on both sides for shaving.

In one aspect the invention consists in a razor having relatively movable cap and guard members which are connected so that they may be separated to receive a blade inserted between them, and being of such construction that they need not be entirely detached for that purpose but may be maintained at all times as parts of a connected assembly, thus avoiding the possibility of loss or misplacement. Also, the construction and arrangement of my improved razor is such that it may be utilized equally well with slotted closed-end blades or slotted open-end blades; that is to say, blades having a longitudinal medial slot opening out through one of the end edges of the blade.

With these and other objects in view, an important feature of my invention consists in cooperating cap and guard members having an interposed spring performing the double function of tending always to separate the cap and guard members of the razor, and of frictionally retaining a blade presented in shaving position between them, even when the cap and guard themselves are separated so that the blade is subjected to no clamping pressure. This contributes to the security and satisfaction of the user in that having once presented a blade in shaving position, either by hand or from a magazine, he has assurance that it will remain properly placed until he can conveniently clamp it for shaving. Further, at the conclusion of the shaving operation, when the cap and guard are separated and clamping pressure is relaxed upon the blade, he has assurance that the used blade will not fall out of the razor but will remain conveniently positioned for him to grasp and remove when he is ready to do so.

These and other features of the invention will be best understood and appreciated from the following description of a preferred embodiment thereof selected for purposes of illustration and shown in the accompanying drawings in which:

Fig. 1 is a view in perspective, on an enlarged scale, of the parts of the razor and a blade in exploded relation, a portion of the razor handle being shown as broken away;

Fig. 2 is a view in perspective of the razor on the same enlarged scale showing the cap and guard members separated and having a blade inserted between them;

Fig. 3 is a view of the razor in longitudinal section in condition corresponding to Fig. 2;

Fig. 4 is a similar sectional view of the razor showing the cap and guard in clamped position; and

Figs. 5 and 6 are views of the razor-head in cross-section corresponding to Figs. 3 and 4 respectively.

The illustrated razor in its general construction is of the "Gillette" type, in that it includes cooperating cap and guard members shaped to impart transverse curvature to a flexible blade presented between them and to clamp and support the blade in that condition for shaving. It will be understood, however, that the invention is not restricted to that or to any particular type of safety razor but with suitable modifications may be embodied in any safety razor employing replaceable blades.

The razor as herein shown is designed to employ a double-edged blade of the character shown in Fig. 1. This blade 10 is generally rectangular in outline and provided in each of its four corners with a reentrant notch. The notches at each end of the blade define elongated unsharpened end portions 11. The blade is sharpened along both longitudinal edges and provided with a longitudinal medial slot 12 substantially as long as the sharpened edges of the blade and terminating in a curved transverse enlargement at each end. The slot 12 has a central circular enlargement or aperture 13 and other intermediate enlargements shaped to fit blade locating projections of different razors in which the blade is adapted for use.

The razor is adapted, in certain details of its structure to accommodate the illustrated blade and it will be understood that for handling blades of different outline corresponding changes in construction of the razor may be made, all within the scope of the present invention. The blade-supporting or guard member 14 of the razor presents an upper blade-engaging face of convex curvature having outwardly and downwardly curved guard teeth 15 disposed along both of its longitudinal edges. At its right-hand end, as shown in Figs. 1 and 3, the guard member is provided with a shallow notch or recess 16 to facilitate presentation or removal of a blade from the razor. A short blade-locating rib 17 projects from the upper face of the guard member adjacent to the end containing the notch 16. A central threaded aperture 18 is provided for connection with the correspondingly threaded end of the handle and a pair of clearance recesses 19 is

provided between the central aperture and the other end of the guard member. Finally, this member is provided in its left-hand end with a pair of spaced notches 20 to receive spaced arms projecting downwardly from the cap member.

The handle of the razor comprises an outer sleeve or barrel 21 having its upper end 22 threaded for connection with the threaded aperture 18 of the guard member. Within the sleeve member of the handle is placed a spindle 23 threaded at its upper end 24 for connection with the cap member, as will presently appear, and having spaced shoulders 25 which cooperate with an internal circumferential rib 26 in the sleeve member of the handle to limit the longitudinal movement of the spindle 23 in the handle while leaving it at all times free for rotation.

Cooperating with the blade-supporting or guard member 14 is a cap member 27 which is of similar outline but somewhat narrower than the guard. The inner face of the cap is transversely curved in a concave manner for flexing a blade in cooperation with the convex face of the guard. It is provided with a longitudinal slot 28 which affords clearance for the blade-locating rib 17 of the guard when the cap and guard are moved into blade-clamping relation. Centrally the cap is provided with a threaded aperture 29 for the reception of the threaded end 24 of the spindle 23.

As shown in Figs. 1 and 2, the cap member 27 has also a shallow recess or notch 30 at its right-hand end corresponding to and supplementing the notch 16 of the guard. At its left-hand end, as shown in Fig. 1, the cap is provided with a pair of spaced downwardly-extending arms 31 which support an underlying retaining plate 32 herein shown as formed integral with the arms 31 and the cap itself. In the assembled razor, the retaining plate 32 extends inwardly beneath the guard member, and is apertured to embrace the upper end of the sleeve portion 21 of the handle and thus constitutes a connecting link between the cap and the guard members. The downwardly extending arms 31 of the cap member are spaced to receive the elongated unsharpened end 11 of a blade as it is advanced into shaving position between the cap and guard and to locate that end of the blade accurately both transversely and longitudinally in the razor-head; that is to say, the arms of the cap arrest the blade when its central circular aperture 13 is in registration with the threaded aperture 29 of the cap.

A curved leaf-spring 33 is interposed between the cap and guard members in a location between the axis of the razor handle and the left-hand end of these members. This spring is transversely curved on a radius substantially smaller than that of the blade-clamping faces of the cap and guard members and so proportioned that it tends always to separate these two members to the maximum distance permitted by engagement of the down-turned arms 31 of the cap member and the underlying plate 32. A shallow recess 34 is provided in the blade-engaging face of the cap member and this recess is of such dimensions that the spring fits into it in substantially flush relation when the cap and guard are clamped together. The curved spring has a pair of spaced perforations 35 which receive a corresponding pair of spaced pins 36 projecting downwardly from the inner face of the cap member, these pins being received with clearance in the spaced recess 19 of the guard

member above mentioned. The natural curvature of the spring is such that it cannot disengage itself from the retaining pins 36 of the cap member so long as the cap and guard are connected by the underlying plate 32. When permitted to do so, the spring maintains the cap member 27 in elevated position, as shown in Figs. 3 and 5, in which the lower ends of the spaced pins of the cap are shown as maintained a substantial distance above the convex blade-engaging face of the guard member 14 thus permitting a blade to be inserted and advanced beneath them. The forward or right-hand end of the spring 33 is curved or beveled forwardly and inwardly and its side edges thus rise in a smooth curve from contact with the face of the guard member. Accordingly, the advancing end of an interposed blade will pass beneath the edges of the spring 33 and will be yieldingly engaged between the edges of the spring and the blade-engaging face of the guard member.

In preparing the razor for shaving, the spindle 23 is rotated reversely until its upper end is disengaged from the threaded aperture 29 of the cap member. When this occurs, the spindle drops by gravity until its upper shoulder 25 rests upon the circumferential rib 26 of the handle sleeve. In this position the upper end 24 of the spindle is retracted below the surface of the guard member and the space between the cap and guard members is clear except for the blade-positioning rib 17 of the guard member, which does not reach the inner surface of the cap member, and the retaining pins 36 of the cap member, which do not reach the blade-engaging face of the guard member.

The user is now free to insert a blade 10 between the two blade-clamping members positioned as suggested in Fig. 3. This may be done either by hand or by discharging the blade from a magazine and in either case the presentation step is facilitated by the notches or recesses 16 and 30 at the right-hand ends of the cap and guard members. As the blade is presented its advancing end 11 first rides up upon the blade-locating rib 17 of the guard member but by the time its end reaches mid-position, it has passed over the blade-locating rib and the slot 12 allows the blade to settle itself upon the convex face of the guard member with the sides of the blade straddling the blade-locating rib. If an open-end blade is employed, its two side portions will immediately straddle the blade-locating rib 17 of the guard member, but in either case the blade is located centrally in the razor-head and its circular aperture 13 guided into registration with the apertures 18 and 29 of the cap and guard members.

As the advancing end 11 of the blade progresses beyond the centre of the razor head, it passes beneath the bowed end of the spring 33 and is yieldingly and continuously clamped by the spring against the upper face of the guard member. This yielding engagement of the blade continues until the blade is fully settled in shaving position with its end 11 positively centered and located between the downturned arms 31 of the cap member. The user is now free to lift the spindle 23, thread its upper end 24 into the threaded aperture 29 of the cap member and screw the spindle home, thus drawing the cap and guard members into clamping engagement with the blade, flexing it as shown in Fig. 6 and supporting both of its edges for the shaving operation. Meanwhile, of course, the curved

spring 33 has been flattened and forced into its recess 34 in the inner face of the cap member 27 and the retaining plate 32 has been forced downwardly into spaced relation with the bottom of the guard member, all as shown in Fig. 6. While the blade-clamping relation is maintained by the cap and guard members, the blade-locating rib 17 of the guard is received in the clearance slot 28 of the cap and the lower ends of the retaining pins 36 of the cap are received in the clearance recesses 19 of the guard.

At the conclusion of the shaving operation, the user may turn the spindle 23 reversely, disengaging it from the cap member and permitting the spring action to separate the cap and guard members while the spring 33 still maintains the blade frictionally in its position until actually removed from the razor by the user. It will be seen that the rib 17 and the spring 33 are spaced from each other at their inner ends sufficiently to permit the spindle end 24 to move freely between them in being connected to or disengaged from the threaded aperture 29 of the cap.

It will be understood that the end 22 of the handle barrel is firmly screwed into the threaded aperture 18 of the guard member and that in ordinary shaving use of the razor this connection is not disturbed. However, if it should be desired to disassemble the razor for repairs or special cleaning, the handle may be unscrewed from the guard member and in this case the cap may be freely removed and the spring 33 detached from the retaining pins 36. The razor head is thus separated into its individual parts and its parts made freely accessible if occasion demands.

Having thus disclosed my invention and described in detail an illustrative embodiment thereof, I claim as new and desire to secure by Letters Patent:

1. A safety razor having cooperating blade-clamping members connected to permit separation for the reception of a thin flexible blade between them, means for limiting the separation of said members, together with a curved leaf spring having a blade-engaging portion and being interposed between the said members and having the double function of separating said members and of frictionally retaining a blade inserted in contact with one of them.

2. A safety razor comprising a handle, a guard member fast thereon, a cap member movably mounted above the guard and having a retaining portion extending below the guard, and a curved spring located between the said two members and having the functions of separating them

and of yieldingly holding a blade in contact with said guard member.

3. A safety razor comprising cooperating blade-clamping members connected for limited separation to receive a blade inserted between them, and a transversely curved spring retained between said members, tending always to separate them and engaging an interposed blade near its opposite edges.

10 4. A safety razor comprising cooperating blade-clamping members connected for limited separation to receive a blade inserted between them, a transversely curved spring, and retaining means engaging the spring at an intermediate point between said members thereby leaving the edges of the spring free to engage a blade.

5. A safety razor comprising opposed blade-clamping members, a transversely curved spring interposed between them, and means for retaining said spring with its convex face in contact with one member and its edges in contact with the other member.

20 6. A safety razor including in its structure a guard having a convex blade-engaging face and a cap having a correspondingly concave blade-engaging face, and a spring interposed between said members and having transversely spaced parallel edge portions maintained in yielding contact with the guard and curved longitudinally away from the face of the guard to facilitate the insertion of a blade between the guard and said spring.

30 7. A safety razor having opposed elongated cap and guard members, a blade-locating rib disposed between the cap and guard adjacent one end thereof, and a convex spring located between the cap and guard adjacent to the other end thereof and having spaced edges beveled to meet a blade inserted endwise on the said guard.

40 8. A safety razor having opposed cap and guard members, a blade locating rib on one member adjacent one end thereof, a transversely curved spring connected to one member adjacent to the other end thereof, and a threaded clamping device movable in the space between said rib and spring.

9. A safety razor comprising cap and guard members having respectively opposed convex and concave faces, the member having the concave face being provided with a shallow recess disposed between parallel blade-shaping edges, means for clamping a blade between said members, and a curved spring interposed between them and shaped to lie within said recess when 50 a blade is clamped in shaving position.

NICHOLAS TESTI.
